UNITED STATES PATENT OFFICE.

CHARLES B. PAGE AND WARREN DEAN BURTON, OF EVANSTON, ILLINOIS, ASSIGNEES
TO GEORGE W. DULANY, JR., OF CHICAGO, ILLINOIS.

COOLING SYSTEM.

Application filed October 12, 1925. Serial No. 62,061.

This invention relates to cooling or condensing systems adapted to cool water or condense steam. The invention has especial reference to apparatus for condensing the 5 steam exhausted from an engine or turbine operated to drive a locomotive or a car. The object of the invention, generally stated, is to provide efficient means for supplying air to the radiators in which water is cooled or 10 steam condensed. Subordinate features of the invention will be pointed out as the description proceeds.

In the accompanying drawings, Figure 1 is a transverse vertical sectional view of a 15 railway car body embodying the features of our invention.

Fig. 2 is a fragmental section on the line 2—2 of Fig. 1.

Fig. 3 is a fragmental sectional view of 20 an alternative construction.

Fig. 4 is a view similar to Fig. 1 but illustrating an alternative construction.

Fig. 5 is a longitudinal sectional view on dotted line 5—5 of Fig. 4.

25 Figure 1, which is more or less diagrammatic, indicates at 1 a railway car body on the roof of which are located a plurality of radiators or condensers 2. Between the radiators 2 is located a chamber or header 3 which extends longitudinally of and in the central vertical plane of the car. As will be noted upon reference to our copending application Serial No. 62,062, filed October 12, 1925, there may be a plurality of radiators 2 at each side of the header 3. Steam 30 may be admitted to the header 3 in any preferred manner, as by means of a pipe, the end of which is indicated at 4. To assist in condensing the steam, water may be sprayed thereon by means of a spray pipe 5 (Fig. 5) extending longitudinally of and within the upper part of the header 3. Steam and water flow from the header 3 to the radiators 2, the latter being inclined downwardly so as to 35 conduct the water to the outlet headers 6.

Instead of employing a single header 3 between the radiators 2 as shown in Fig. 1, each radiator or bank of radiators may be provided with a separate header 3^a as shown 50 in Fig. 3, each header containing a perforated pipe 5^a for spraying water upon the incoming exhaust steam.

Means is provided for forcing air through the radiators 2, said means being herein 55 shown as duplicated at the opposite sides of

the car body. For each radiator 2, there is provided a fan 7 located below the car body and driven by any preferred means, as, for example, that fully disclosed in said application Ser. No. 62,062.

60 The air discharged from each fan 7 is conducted to the radiator 2 by means of a conduit 8. Dampers 8^a in the conduits 8 permit of regulating the flow according to outside temperature conditions. Each conduit 8 65 comprises a vertical portion 9 and an upwardly inclined portion 10, the latter underlying the radiator. In the illustrative embodiment shown in the drawings, the conduit portions 10 extend to the longitudinal 70 center line of the car body and communicate with each other. At the junction of the conduit portions 9 and 10 we provide means to prevent the major portion of the air from passing more or less directly up through the 75 lower end of the radiator, said means comprising a baffle plate 11 located within the conduit 8 in position to divide the column of air rising in the conduit portion 9 into two substantially equal portions, said baffle 80 extending sufficiently far into the conduit portion 9 so as to direct the inner or lower portion of said column of air to the upper or inner portion of the radiator. The air supplied by the fans 7 is thereby distributed 85 with substantial uniformity to all parts of the radiators.

If desired, the fans or blowers may be located within the car body and close to the condensers, as shown in Fig. 4. The fans 90 12 draw air through louvers 13 in the sides of the car.

If desired, a baffle 14 may be provided upon the car roof directly in front of the radiators 2 so that in the travel of the car, 95 air striking said baffle shall be deflected upwardly over the radiators, thus reducing atmospheric pressure over the radiators and thereby accelerating the flow of air from the conduits through the radiators. 15 are side 100 walls extending from the ends of the baffle 12 to the rear end of the radiators.

It will be seen that we have provided simple and effective means for supplying air to the radiators of a steam condensing system 105 or the like.

We claim as our invention:

1. The combination of a vehicle body, a radiator located in an inclined position on said body, a fan below said body, a conduit 110

at one side of the body, extending from the fan to the radiator, and a baffle within said conduit near the lower end of the radiator for dividing the air current in said conduit 5 and directing a portion thereof to the upper portion of the radiator.

2. The combination of a vehicle body, two radiators located on top of said body at opposite sides of the central vertical plane of 10 the body, and inclined downwardly toward the sides of the body, each radiator having a separate steam inlet header at its upper end, a water spray pipe in each inlet header, two fans below and at opposite sides of the body 15 and two conduits at opposite sides of the body, each extending from one of said fans to the corresponding radiator.

3. The combination of a passenger vehicle body, two radiators located on the roof of 20 said body at opposite sides of the central vertical plane of the body, two fans below and at opposite sides of the body, two conduits at opposite sides of the body, for delivering air from said fans to the radiators, 25 and a baffle located on the roof of said body in advance of said radiators for deflecting air upwardly above said radiators and thus accelerating the flow of air through the latter.

30 4. The combination of a passenger vehicle body, two radiators located on top of said body at opposite sides of the central vertical plane of the body, two fans below and

at opposite sides of the body, and two conduits at opposite sides of the body, each extending from one of said fans to the corresponding radiator. 35

5. The combination of a passenger vehicle body, a radiator located on top of the body, a fan below the body, and a conduit for conveying air from said fan to said radiator. 40

6. The combination of a passenger vehicle body, a radiator located on top of said body, a fan for forcing air through said radiator, and a baffle located on said body in advance 45 of the radiator for deflecting air upwardly above said radiator and thus accelerating the flow of air through the latter.

7. The combination of a car body, a radiator located on top of said body, means for admitting steam to the radiator, means for spraying water on the incoming steam, and a fan for causing a flow of air through the radiator. 50

8. The combination of a car body, a radiator located on top of said body, means for admitting steam to the radiator, means for spraying water on the incoming steam, a fan located at one side of the car body, and a conduit for conveying air from said fan 60 to said radiator. 55

In testimony whereof we have hereunto affixed our signatures.

CHARLES B. PAGE.
WARREN DEAN BURTON.
